UNITED STATES PATENT OFFICE.

T. CHALKLEY TAYLOR, OF PHILADELPHIA, PENNSYLVANIA.

PACKING CAUSTIC ALKALI.

SPECIFICATION forming part of Letters Patent No. 270,997, dated January 23, 1883.

Application filed May 29, 1882. (No specimens.)

To all whom it may concern:

Be it known that I, T. CHALKLEY TAYLOR, a citizen of the United States of America, residing at Philadelphia, in the county of Philadelphia and State of Pennsylvania, have invented certain new and useful Improvements in Compressing and Cementing Caustic Alkalies, of which the following is a specification.

My invention has relation to processes for cementing and compressing the alkalies of soda and potassa in convenient form or blocks, and then coating the compressed mass with a water-proof solution to prevent deliquescence, so that the blocks may be placed on the market in a very convenient form, readily admit of handling, and remain in a perfect state of preservation for an indefinite length of time.

In practice I take granulated alkalies—as soda or potash—and mix with them about twenty per cent. of resinous or fatty matter, so as to form a plastic mass. It is then divided into convenient balls or packages for market—say about one pound each. These packages are then by any suitable means separately com-

25 pressed into a compact mass, the fatty or resinous matter having a tendency to cement the

whole together. After the packages or balls are removed from the press they are then covered with a water-proof coating, which will prevent deliquescence.

In practice I prefer to make this coating of such material as will ultimately enter into the composition of soap when the balls are used for that purpose.

Having thus fully described my invention, 35 what I claim, and desire to secure by Letters Patent of the United States, is—

The process of making balls or blocks of caustic alkali which consists in mixing with the pulverized or powdered alkali a portion of 40 resinous or fatty matter, compressing the compound into balls or blocks of suitable size, and finally coating said balls or blocks with a suitable coating to prevent deliquescence, as set forth.

In testimony whereof I affix my signature in presence of two witnesses.

T. CHALKLEY TAYLOR.

Witnesses:

E. H. BRADFORD,
H. J. ENNIS.
